END-ATTACHING DEVICE

Eugen F. Prestinari, Short Hills, and John F. Sand, Newark, N. J., assignors to Gemex Company, Union, N. J., a corporation of New Jersey

Application January 3, 1950, Serial No. 136,557

10 Claims. (Cl. 24—248)

1

This invention relates to end-attaching devices, and more particularly to devices of this class such as are used on the end of a snake chain portion of a snake chain wrist watch band for attaching the end of the chain to the clasp of the band.

The principal object of the invention is the provision of an end-attaching device of the class described by means of which the end of a snake chain or the like may be readily and securely detachably connected to the clasp of a wrist watch bracelet or other member, from which the end of the chain may be readily released so that the chain may be shortened if necessary and its end re-attached to the device without damaging the chain or the device, and which has a perfectly smooth surface in contact with the wrist of the wearer so that it will not injure or irritate the skin. Briefly, an end-attaching device of this invention comprises a channel member adapted to receive the end of a snake chain or the like. Inwardly directed opposed teeth are provided at the sides of the channel member adapted to enter between two adjacent links of a snake chain or the like inserted between the flanges of the channel member to prevent the chain from being pulled endwise out of the channel. A closure is provided for the open side of the channel to prevent removal of the end of the chain through the open side of the channel. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which several of various possible embodiments of the invention are illustrated,

Fig. 1 is a plan view of an end-attaching device of the invention for a snake chain of rectangular cross section;

Fig. 2 is a side elevation of Fig. 1;

Fig. 3 is a bottom plan view of Fig. 1;

Fig. 4 is a longitudinal section taken on line 4—4 of Fig. 2;

Fig. 5 is a transverse section taken on line 5—5 of Fig. 1, the chain being omitted;

Fig. 6 is a longitudinal section taken on line 6—6 of Fig. 1, illustrating certain jaws of the device in open position, the chain being omitted;

Fig. 7 is an exploded perspective view illustrating the elements of the device of Fig. 1;

2

Fig. 8 is a section similar to Fig. 5 showing a modification for accommodating a snake chain of circular cross section, the chain being shown in dotted lines;

Fig. 9 is a perspective view of a special gripper element for the Fig. 8 embodiment;

Fig. 10 is a section similar to Fig. 5 showing a modification for accommodating two snake chains of rectangular cross section side-by-side, the chains being shown in dotted lines; and,

Fig. 11 is a section similar to Fig. 5 illustrating a modification for accommodating two snake chains of circular cross section side-by-side, the chains being shown in dotted lines.

Similar reference characters indicate corresponding parts throughout the several views of the drawings.

Referring to the drawings, Figs. 1—7 illustrate an end-attaching device of this invention for accommodating a snake chain C of rectangular cross section. Snake chains of the type for which this end-attaching device is adapted are well known in the jewelry art and require no further description. As shown, the end-attaching device comprises a channel member 1 and a pivoted closure 3 for closing the open side of the channel member. The channel member 1 is of U-shape in cross section having a flat web 5 and straight flanges 7 perpendicular to the web. The closure 3, which is also of channel shape in cross section, has a flat web 9 and straight flanges 11 perpendicular to the web. The channel member 1 is of such width as to have a close frictional fit between the flanges 11 of the closure 3. The flanges 7 of the channel member 1 correspond in height to the flanges 11 of the closure 3 so that the channel member may fit substantially entirely within the closure. The web 9 of the closure 3 terminates short of one end thereof, so that the flanges 11 of the closure project past this end of the web, as indicated at 13. A fingernail tab 15 projects from the other end of the web 9 of the closure.

The channel member 1 is somewhat longer than the closure 3. The web 5 of the channel member 1 slopes inward at one end as indicated at 17. An opening 19 is provided in the sloping portion 17 for receiving a link 21 (shown in dotted lines in Figs. 1—3) for attaching the device to the clasp 23 (shown fragmentarily in dotted lines in Figs. 1—3) of a wrist watch bracelet. The channel member 1 is pivoted adjacent its end where the opening 19 is provided between the projecting portions 13 of the flanges 11 of the closure 3 by means of a pivot pin 25. The latter extends

from one flange 11 of the closure through the flanges 7 of the channel member 1 to the other flange 11 of the closure, and its other ends are staked in place in the flanges 11 of the closure. The channel member 1 and the closure 3 are pivotally connected together at one end by the pin 25 in opposed relation, i. e., the open side of the channel member 1 faces the open side of the closure 3. The arrangement is such that the channel member 1 and the closure may be pivoted to a closed position wherein they form a box-like socket open at the end remote from the pivotal connection at the pin.

At 27 is shown a U-shaped gripper element for gripping the end of the snake chain C. The gripper has arms 29 extending from a base portion 31, the arms being springy. The gripper may be bent from a strip of sheet metal. The channel member 1 is made somewhat wider than the width of the snake chain C. The gripper is slightly narrower than the channel member 1 so that its arms fit tightly between the sides of the snake chain and the flanges 7 of the channel member 1 when the end of the snake chain is inserted between the arms of the gripper (see Fig. 4), the arms of the gripper being spaced apart a distance corresponding to the width of the snake chain. The gripper is pivoted on the pin 25 adjacent its base 31, the pin extending through apertures 32 provided in the arms 29 of the gripper adjacent the base 31. The gripper is located between the sides of the channel member 1 and its arms 29 extend forward from the pin 25 toward the free end of the channel member at the sides of the channel member. Each arm of the gripper is shown as formed at its forward free end with a pair of inwardly directed teeth 33, the teeth of the two arms being opposed and adapted to enter between adjacent links of the snake chain C as illustrated in Fig. 4. It will be understood that each arm of the gripper may be formed with only one tooth, rather than a pair, or more than two teeth spaced at intervals corresponding to the spacing of the links of the snake chain, if desired. The arms 29 of the gripper terminate somewhat short of the free end of the channel member 1.

The closure 3 may be releasably maintained in closed position closing the open side of the channel member 1 by providing detents 35 struck inward from the flanges of the closure 3 engageable in apertures 37 formed in the flanges of the member 1. However, the member 1 may be formed to have such a close sliding fit between the flanges of the closure 3 that the friction between the flanges will releasably maintain the closure 3 in closed position without such detents.

As shown, the gripper element 27 is formed with outwardly struck detents 38 adjacent the free ends of its arms 29. These are engageable in apertures 40 in the side flanges 7 of the channel member 1 to prevent the gripper element from pivoting out from between the flanges 7. The detents 38 and apertures 40 may be omitted if it is not desired to keep the gripper element from swinging out from between the flanges 7.

To attach the end of the snake chain C to the device, the members 1 and 3 are opened to a position such as illustrated in Fig. 6, utilizing the fingernail tab 15 for this purpose. The end of the snake chain is then inserted between the members 1 and 3, and pressed in between the arms 29 of the gripper 27, the teeth 33 at the ends of the arms entering the space between adjacent links of the chain. Then the closure 3 is closed. The flanges 7 of the channel member 1

prevent the arms 27 of the gripper from spreading apart so that the teeth 33 prevent the chain from being pulled out endwise. The closure 3, which is releasably held in position closing the open side of the channel member 1, either by the engagement of detents 35 in apertures 37, or by the frictional engagement of the inner and outer flanges 7 and 11 if the detents are not used, prevents removal of the chain through the open side of the channel member.

It will be understood that as an alternative to the above-described mode of attaching the end of the snake chain to the device, the end of the chain may be inserted in the closure 3 and the closure and channel member 1 pressed together to cause the end of the chain to enter between the arms of the gripper. Under these circumstances, the teeth 33 at the ends of the arms of the gripper find the nearest spaces between adjacent links of the chain and bite in between these links.

To release the end of the chain, the closure 3 is opened, and the end of the chain is slipped sidewise off the teeth of the gripper. No damage is done either to the chain or to the end-attaching device in attaching or releasing the end of the chain.

As herein illustrated, the arrangement is such that the outside face of the web 9 of the closure 3 contacts the wrist of the wearer. It will be seen that the outside face of the closure is perfectly smooth and will not irritate or injure the skin. Nor are there any sharp corners in any such position that would contact the wrist.

Fig. 8 illustrates a modification for accommodating a snake chain of circular cross section. This modification is in most respects the same as that of Figs. 1-7 except that the web of the channel member 1 is arcuately curved as indicated at 39 to fit the chain of circular cross section, and the teeth at the ends of the arms 29 of the gripper 27 are formed as shown at 41 in Figs. 8 and 9, with only one tooth on each arm of the gripper. This modification is also shown with detents 35 and 38 and apertures 37 and 40 omitted, to indicate that they are not essential.

Fig. 10 illustrates a modification for accommodating two snake chains of rectangular cross section side-by-side. This modification is the same in most respects as that of Figs. 1-7 except that the channel member 1 and the closure 3 are made wider to receive the two chains. This modification is also shown with detents 35 and 38 and apertures 37 and 40 omitted.

Fig. 11 illustrates a modification for accommodating two snake chains of circular cross section side-by-side. This modification is in all respects the same as that of Fig. 10 except that the web of the channel member 1 is doubly arcuately curved as indicated at 43 and the teeth at the ends of the arms 29 of the gripper 27 are formed as shown in Fig. 9.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. An end-attaching device for a snake chain or the like comprising a channel member of

U-shape in cross section thereby having a web, side flanges, and an open side, a U-shaped gripper pivoted between the flanges of the channel member adjacent one end of the latter with its arms extending along the insides of the flanges of the channel member and spaced apart to receive the end of a snake chain or the like therebetween, each arm of the gripper having an inwardly directed tooth at its end, and a closure for the open side of the channel member pivoted on the pivotal connection of the gripper and the channel member.

2. An end-attaching device for a snake chain or the like comprising a channel member of U-shape in cross section thereby having a web, side flanges, and an open side, a U-shaped gripper pivoted between the flanges of the channel member adjacent one end of the latter with its arms extending along the insides of the flanges of the channel member and spaced apart to receive the end of a snake chain or the like therebetween, each arm of the gripper having an inwardly directed tooth at its end, and a closure for the open side of the channel member pivoted on the pivotal connection of the gripper and the channel member, said closure being of U-shape in cross section thereby having a web, side flanges, and an open side and having its open side opposed to the open side of the channel member, the latter being adapted to fit tightly but releasably in the closure.

3. An end-attaching device for a snake chain or the like comprising a channel member of U-shape in cross section thereby having a web, straight side flanges perpendicular to the web, and an open side, a closure of U-shape in cross section thereby having a web, straight side flanges perpendicular to the web, and an open side, the channel member being adapted to fit tightly but releasably in the closure, the channel member and closure being pivotally connected at one end with their open sides in opposed relation by means of a transverse pin fixed at its ends in the flanges of the closure and extending through the flanges of the channel member, and a U-shaped gripper pivoted at its base end on the pin with its arms extending toward the free end of the channel member along the insides of the flanges of the channel member, each arm of the gripper having an inwardly directed tooth at its end adapted to enter between two adjacent links of the end of a snake chain or the like laterally inserted between the arms of the gripper.

4. An end-attaching device for a snake chain or the like comprising a channel member of U-shape in cross section thereby having a web, straight side flanges perpendicular to the web, and an open side, a closure of U-shape in cross section thereby having a web, straight side flanges perpendicular to the web, and an open side the channel member being adapted to fit tightly but releasably in the closure, the channel member and closure being pivotally connected at one end with their open sides in opposed relation by means of a transverse pin fixed at its ends in the flanges of the closure and extending through the flanges of the channel member, and a U-shaped gripper pivoted at its base end on the pin with its arms extending toward the free end of the channel member along the insides of the flanges of the channel member, each arm of the gripper having an inwardly directed tooth at its end adapted to enter between two adjacent links of the end of a snake chain or the like laterally in-

serted between the arms of the gripper, the web of said channel member having an opening therein at the pivoted end of the channel member to receive a link for attaching the device to a bracelet clasp or the like.

5. An end-attaching device for a snake chain or the like comprising a channel member of U-shape in cross section thereby having a web, straight side flanges perpendicular to the web, and an open side, a closure of U-shape in cross section thereby having a web, straight side flanges perpendicular to the web, and an open side the channel member being adapted to fit tightly but releasably in the closure, the channel member and closure being pivotally connected at one end with their open sides in opposed relation by means of a transverse pin fixed at its ends in the flanges of the closure and extending through the flanges of the channel member, and a U-shaped gripper pivoted at its base end on the pin with its arms extending toward the free end of the channel member along the insides of the flanges of the channel member, each arm of the gripper having an inwardly directed tooth at its end adapted to enter between two adjacent links of the end of a snake chain or the like laterally inserted between the arms of the gripper, the web of said closure being smooth and flat and having a fingernail tab projecting from its end at the free end of the closure.

6. An end-attaching device for a snake chain or the like comprising a channel member having a web and straight flanges perpendicular to the web, one end of the web sloping inward toward the respective end of the channel member and having an opening therein to receive a link for attaching the channel member to a bracelet clasp or the like, a closure of channel shape having a web and straight flanges, the web of the closure terminating short of one end of the closure so that its flanges project past this end of the web, the channel member being adapted to fit tightly but releasably in the closure, the channel member and closure being pivotally connected together with their open sides in opposed relation by means of a transverse pin fixed at its ends in the projecting portions of the flanges of the closure and extending through the flanges of the channel member adjacent the end of the latter provided with the link-receiving opening, and a U-shaped gripper pivoted at its base end on the pin, the pin extending through openings in the arms of the gripper adjacent its base, with the arms of the gripper extending toward the free end of the channel member along the insides of the flanges of the channel member, each arm of the gripper having an inwardly directed tooth at its end adapted to enter between two adjacent links of the end of a snake chain or the like inserted between the arms of the gripper.

7. An end-attaching device for a snake chain or the like comprising a channel member having a web and straight flanges perpendicular to the web, one end of the web sloping inward toward the respective end of the channel member and having an opening therein to receive a link for attaching the channel member to a bracelet clasp or the like, a closure of channel shape having a web and straight flanges, the web of the closure terminating short of one end of the closure so that its flanges project past this end of the web, the channel member being adapted to fit tightly but releasably in the closure, the channel member and closure being pivotally connected to-

gether with their open sides in opposed relation by means of a transverse pin fixed at its ends in the projecting portions of the flanges of the closure and extending through the flanges of the channel member adjacent the end of the latter provided with the link-receiving opening, and a U-shaped gripper pivoted at its base end on the pin, the pin extending through openings in the arms of the gripper adjacent its base, with the arms of the gripper extending toward the free end of the channel member along the insides of the flanges of the channel member, each arm of the gripper having an inwardly directed tooth at its end adapted to enter between two adjacent links of the end of a snake chain or the like inserted between the arms of the gripper, the web of said closure being smooth and flat and having a fingernail tab projecting from its end at the free end of the closure.

8. An end-attaching device as set forth in claim 7, further including detents extending inward from the flanges of the closure engageable in apertures in the flanges of the channel member.

9. An end-attaching device as set forth in 25

claim 7, further including means for preventing the gripper from pivoting out from between the flanges of the channel member.

10. An end-attaching device as set forth in claim 7, further including detents extending outward from the arms of the gripper engageable in apertures in the flanges of the channel member.
